A. D. NEWCOMB.

LIFEBOAT.

APPLICATION FILED MAR. 10, 1917.

Patented Feb. 28, 1922.

UNITED STATES PATENT OFFICE.

ALCANZO D. NEWCOMB, OF NORFOLK, VIRGINIA, ASSIGNOR, BY MESNE ASSIGNMENTS, OF ONE-HALF TO RICHARD D. L. FLETCHER, OF CAPE CHARLES, VIRGINIA, AND ONE-HALF TO ROBERT T. MARSH, OF RICHMOND, VIRGINIA.

LIFEBOAT.

1,408,130.

Specification of Letters Patent. Patented Feb. 28, 1922.

Application filed March 10, 1917. Serial No. 153,867.

(GRANTED UNDER THE PROVISIONS OF THE ACT OF MARCH 3, 1921, 41 STAT. L., 1313.)

To all whom it may concern:

Be it known that I, ALCANZO D. NEWCOMB, a citizen of the United States, residing at Norfolk, in the county of Norfolk and 5 State of Virginia, have invented certain new and useful Improvements in Lifeboats, of which the following is a specification.

My invention relates to new and useful 10 improvements in life boats. The object of my invention is to provide a life boat preferably made of steel, which can be totally submerged, and having means for automatically closing the air ports when submerged, and provided with means where- 15 by the boat can be released from the lashings holding it upon the deck from below the deck.

Another object of my invention is to provide a boat of this character having oars 20 which may be inserted or removed from below the deck and which can also be operated from below the deck and also providing means for raising or removing persons from the open water.

A still further object of my invention is 25 to provide a simple and effective arrangement of parts, having certain combinations hereinafter more fully set forth.

In the accompanying drawings—

Figure 1 is a top plan view of my im- 30 proved life boat;

Figure 2 is a side elevation of Figure 1.

Referring now to the drawings, 1 represents my improved life boat which is pref- 35 erably made of steel and completely covered by the deck 2, which makes a watertight boat, all of which is readily understood. The deck 2 is provided with a series of hatch openings having raised coamings 3 surround- 40 ing the same and upon which rests the hatches 4, there being any desired numbers of hatch openings and a hatch for each opening. The hatches 4 have at one side the out- 45 wardly extending ears 5 pivoted to the ears 6 carried by the upper face of the deck 2 and whereby the hatches may be swung up- 50 wardly for opening the same. The hatches are held in their closed position on the coaming by means of the pivoted latches operated

I have shown three of these hatches 5, but it will be understood that any desired number may be used without departing from my in- 55 vention.

The side of the boat is provided with an inwardly extending or bent portion 7 ar- 60 ranged on each side and in which are ar- ranged the air intake openings 8 communi- 65 cating with the interior of the boat and ar- ranged in said openings are valves 9 which are normally held open, so that air can pass into the boat and are closed by water pres- 70 sure from the outside of the boat. By this 65 arrangement of the valves, it will be seen that, when the boat is on the surface of the water, it is supplied with the necessary air, but when it is submerged or the waves wash over the boat, the water pressure will auto- 75 matically close the valves. The side of the boat, below the air ports or openings 8, is provided with openings in which are ar- 80 ranged the oar locks 10 which allow the oars to be inserted therethrough from within the 75 boat and having means for preventing water passing into the boat around the oars. The oar lock openings, when the oars are not in use, are closed by removable stoppers, so that water can not enter through said open- 80 ings.

The forward and rear ends of the boat are provided with pivoted davit engaging mem- 85 bers 11 and 12 having pivoted releasing levers 13 and 14 to which are connected the 85 links 15 and 16. The links 15 and 16 are connected by additional links 17 and 18 to the free ends of the intermediately pivoted lever 19. This lever, as shown, is pivoted at 20, to the upper face of the deck and is 90 provided with holding means 21, whereby the lever is held so that the davit engaging members are closed for holding the boat on the davits. By moving the lever 19 on its pivot, it will be seen that the pivoted releas- 95 ing levers 13 and 14 will be moved, so that the davit hooks are released and the boat free to clear the vessel.

The forward and rear ends of the boat in 100 beyond the davit engaging members 11 and 12 are provided with the transverse lashing engaging members 22 and 23, which have connected thereto the pivoted releasing levers 24 and 25 which extend transversely

of the boat and have connected thereto the links 26 and 27 which are connected to the free ends of the lever 28. The lever 28 is pivoted on the pivot 20 of the lever 19 below the deck, whereby the boat may be released from its lashings from below the deck. This allows passengers to enter the life boat and close it up tightly and release it from its lashings after the vessel has or is sinking in the event that it is impossible to launch the boat by means of the davits.

Having thus described my invention, what I claim as new and desire to secure by Letters Patent, is:

- 15 1. The combination with a life boat having a deck completely covering the same, hatches on said deck, air intake valves in the side of the boat and automatically closed by water pressure from the outside, and a lashing releasing mechanism operated from within the boat.
- 20 2. The combination with a life boat having a deck completely covering the same, hatches covering the hatch openings, air intake valves in the sides of the boat and automatically closed by water pressure from the outside, a davit releasing mechanism operated from above the deck, and a lashing releasing mechanism operated from within the boat.
- 25 3. The combination with a life boat having a deck completely covering the same, air intake valves in the sides of the boat and automatically closed by water pressure from the outside, a davit releasing mechanism operated from above the deck, and a lashing releasing mechanism operated from within the boat.
- 30 4. The combination with a life boat having a deck completely covering the same and having hatch openings therein, hatches covering the hatch openings, air intake valves in the sides of the boat and automatically

closed by water pressure from the outside, a davit releasing mechanism operated from 45 the deck, a lashing releasing mechanism operated from within the boat, and ore locks arranged in the sides of the boat below the air intake valves and constructed and arranged to allow the oars to be inserted from 50 within the boat.

5. The combination with a life boat having a deck completely covering the same and having hatch openings, hatches covering the 55 openings, and a lashing releasing mechanism operated from within the boat.

6. The combination with a life boat having a deck completely covering the same and having hatch openings, hatches covering the hatch openings, a lashing releasing mechanism 60 operated from within the boat, and a davit releasing mechanism operated from above the deck.

7. The combination with a life boat having a deck completely covering the same and 65 having hatch openings therein, pivoted hatches closing said hatch openings, air intake valves in the sides of the boat and automatically closed by water pressure from the outside, a davit releasing mechanism operated from above the deck, a lashing releasing mechanism operated from within the boat, and oar locks arranged in the sides 70 of the boat below the air intake valves and constructed and arranged to allow the oars 75 to be inserted from within the boat and to form a water tight joint and having means for closing the same when the oars are not in use.

In testimony whereof I affix my signature 80 in the presence of two witnesses.

ALCANZO D. NEWCOMB.
